US0D1035357S

(12) **United States Design Patent** (10) Patent No.: **US D1,035,357 S**
(45) Date of Patent: ** Jul. 16, 2024

(54) **BENCH**

(71) Applicant: **LANDSCAPE FORMS, INC.**,
Kalamazoo, MI (US)

(72) Inventors: **Brian P. Revoir**, Vicksburg, MI (US);
Sullivan O'Connor, Kalamazoo, MI (US)

(73) Assignee: **LANDSCAPE FORMS, INC.**,
Kalamazoo, MI (US)

(**) Term: **15 Years**

(21) Appl. No.: **29/777,574**

(22) Filed: **Apr. 7, 2021**

(51) LOC (14) Cl. **06-06**

(52) U.S. Cl.

USPC **D6/716.4**

(58) **Field of Classification Search**

CLAIM

The ornamental design for a bench, as shown and described.

DESCRIPTION

FIG. 1 is a first embodiment, perspective view of a bench in accordance with the new design;
FIG. 2 is a front elevational view thereof;
FIG. 3 is a right side elevational view thereof;
FIG. 4 is a left side elevational view thereof;
FIG. 5 is a rear elevational view thereof;
FIG. 6 is a top view thereof;
FIG. 7 is a second embodiment of the bench;
FIG. 8 is a third embodiment, perspective view of the bench;
FIG. 9 is a front elevational view thereof;
FIG. 10 is a right side elevational view thereof;
FIG. 11 is a left side elevational view thereof;
FIG. 12 is a rear elevational view thereof;

FIG. 13 is a top view thereof;
FIG. 14 is a fourth embodiment of the bench;
FIG. 15 is a fifth embodiment, perspective view of the bench;
FIG. 16 is a front elevational view thereof;
FIG. 17 is a right side elevational view thereof;
FIG. 18 is a left side elevational view thereof;
FIG. 19 is a rear elevational view thereof;
FIG. 20 is a top view thereof;
FIG. 21 is a sixth embodiment of the bench;
FIG. 22 is a seventh embodiment, perspective view of the bench;
FIG. 23 is a front elevational view thereof;
FIG. 24 is a right side elevational view thereof;
FIG. 25 is a left side elevational view thereof;
FIG. 26 is a rear elevational view thereof;
FIG. 27 is a top view thereof; and
FIG. 28 is an eighth embodiment of the bench.
The short dashed lines depict portions of the bench that form no part of the claimed design.
The dash-dot-dash lines in figures illustrate boundaries that form no part of the claim.
The long dashed breakaway lines in FIGS. 7, 14, 21, and 28 indicate a symbolic break in the width of the design indicating no specific width. The appearance of any portion of the article between the breakaway lines forms no part of the claimed design.
